UNITED STATES PATENT OFFICE

126,590

DESIGN FOR AN ELECTRICAL OUTLET RECEPTACLE

Jacob W. Lewin, Chicago, Ill.

Application December 24, 1940, Serial No. 97,597

Term of patent 14 years

To all whom it may concern:

Be it known that I, Jacob W. Lewin, a citizen of the United States, residing at Chicago, in the county of Cook and State of Illinois, have invented a new, original, and ornamental Design for an Electrical Outlet Receptacle, of which the following is a specification, reference being had to the accompanying drawing, forming a part thereof.

In the drawing:

Figure 1 is an end elevational view of an elec-

trical outlet receptacle embodying my new design;

Figure 2 is a side elevational view thereof; and
Figure 3 is a top plan view thereof.

The opposite side and end of the receptacle
are substantially similar to those shown.

I claim:

The ornamental design for an electrical outlet receptacle, as shown and described.

JACOB W. LEWIN.
